GUN PERFORATOR CONSTRUCTION

Arthur J. Zschokke, Huntington Park, Calif.,
assignor to Lane-Wells-Company, Los Angeles,
Calif., a corporation of Delaware

Application November 1, 1940, Serial No. 363,831

9 Claims. (Cl. 164—0.5)

My invention relates to gun perforator construction, that is, to devices which are adapted to be lowered within a well casing for firing projectiles through the casing and thereby form passages for the flow of oil from the surrounding formation into the well. Among the objects of my invention are:

First, to provide a gun perforator construction of the general type disclosed in Patents Nos. 2,216,145 and 2,216,151 wherein a large number of electrically fired gun units are incorporated in compact relation in a common cylindrical gun body;

Second, to provide a gun body construction wherein the gun units are arranged helically to afford a substantially uniform radial distribution so that the resulting perforations in the well casing are distributed circumferentially as well as longitudinally;

Third, to provide a gun perforator which incorporates a novel wiring system whereby the gun units may be fired in sequence, the wiring system including an electrical connection between the distributor wires of the system and the individual leads to the several gun units; such connections, although exposed to well fluid pressures, are particularly secure against the surge of liquid around the gun, either during movement of the gun through the well bore or upon discharge of the gun unit;

Fourth, to provide a gun perforator construction wherein the distributor wire system for the gun unit, although exposed to all manner of well fluids and subjected to the extreme temperature conditions normally present within well bores, has a particularly long service life;

Fifth, to provide a gun perforator construction wherein the gun muzzles are disposed circumferentially a maximum distance from the gun unit leads so as to minimize the surge pressures around the exposed parts of the wiring;

Sixth, to provide a gun construction in which the gun units are incorporated integrally in the gun body, the various cavities, channels, gun bores and powder chambers being formed in the gun body and being so disposed with respect to each other that during the course of heat treating the tendency for the gun body to warp is minimized; and

Seventh, to provide a gun perforator construction which is readily and economically manufactured and contains a minimum number of parts as compared with the number of gun units incorporated therein.

With the foregoing and other objects in view, 55 of gun units are located at opposite sides of the

as may appear hereinafter, reference is directed to the accompanying drawing, in which:

Figure 1 is a fragmentary elevational view of a gun perforator construction embodying my invention;

Figure 2 is a transverse sectional view thereof through 2—2 of Figure 1, showing by dotted line the relative positions of other gun units below that through which this section is taken; and

10 Figure 3 is a fragmentary sectional view through 3—3 of Figure 1, showing particularly the electrical connection between the distributor wire and the gun unit lead.

My gun perforator construction comprises a 15 gun body 1 which is cylindrical and of uniform diameter. A plurality of gun bores 2 are drilled laterally into the gun body. These extend almost the diameter of the gun body and are adapted to be closed at their outer ends by water- 20 excluding caps 3.

The gun bores are preferably arranged in two sets which are disposed alternately along the gun body. The gun bores of one set are disposed almost diametrically opposite the adjacent bores 25 of the other set and both sets of gun bores spiral in the same direction around the gun body. Thus, with reference to Figure 2, the uppermost gun bore, designated A, of the first set is directed to the left and the uppermost gun bore, designated B, of the second set is clockwise displaced approximately 120 degrees, while the second gun bore, designated C, of the first set is clockwise displaced about 15 degrees from bore A. Similarly, the second gun bore of the second series is 30 offset only a few degrees from the gun bore B, etc. Thus, by arranging each set of gun bores in a helix having approximately one-half turn, a substantially uniform radial distribution of the gun bores is provided, so that all sides of the 35 casing in which the gun perforator may be mounted can be perforated.

Each gun bore is intersected near its inner end by a cross bore 4 which is disposed at right angles to the gun bore and which defines, with the 45 axis of the gun bore, a plane at right angles to the axis of the gun body. The cross bore receives a main powder cartridge 5 which may extend across the gun bore, and the inner end of the gun bore beyond the cross bore may receive a supplemental cartridge 6. The cartridges 5 and 6 contain a suitable high explosive. A bullet 7 is positioned in the gun bore outwardly of but adjacent the cross bore.

The cross bores or cartridge bores of the two sets 50 of gun units are located at opposite sides of the

axis of the gun body and their points of intersection with the periphery of the gun body define a common helical path approximately 120° displaced from the two helical paths defined by the muzzle ends of the two sets of gun bores.

The outer end of the cross bore 4 is threaded to receive a plug 8. The plug 8 is adapted to receive a lead wire (to be described hereinafter) which extends to the inner end of the plug and coacts with an electrically responsive fuse (not shown) for igniting the cartridge. At the outer end of each cross bore, the gun body is provided with a recess 9 large enough to receive the head of the plug 8.

The gun body is provided with a longitudinal distributor wire channel 10 which extends longitudinally in a helical path so as to remain in the area between the outer or muzzle ends of the several gun bores and the inner ends of their respective cross bores, such position being approximately diametrically opposite from the helical path of the series of plug recesses 9. The distributor wire channel 10 is provided with a cover strip 11 which fits into longitudinal grooves provided near the outer side of the passage, the cover being inserted endwise along the passage.

The base of the distributor wire channel is intersected by a plurality of conductor passages 12, one for each gun unit. These passages extend approximately diametrically in axially offset planes with respect to the gun bores. At the end of each conductor passage, remote from the distributor wire channel, there is provided a counterbore 14 and outwardly from the counterbore a recess 15. Each counterbore 14 receives a connector 16 which comprises a sleeve 17 of insulating material having a bore therethrough which is adapted to be closed at each end by a cork or stopper 18, so that a chamber is formed within the sleeve 17. A conductive liquid 19 such as mercury fills the sleeve between the corks 18.

The distributor wire channel 10 is adapted to receive a plurality of distributor wires 20, preferably one for each gun unit. For convenience, only one of said distributor wires is illustrated. Each distributor wire extends through its conductor passage 12 and is provided with a bare extremity which extends into the conductive liquid 19 through the inner cork of the connector. The outer cork of the connector receives a similar wire 21 which constitutes a gun unit lead. Each gun unit lead extends from its recess 15 through a slot 22 which connects recess 15 with the plug recess 9 and then extends downwardly through the corresponding plug 8 to the main cartridge.

The upper end of the distributor wire channel 10 connects with a socket 23 formed in the upper end of the gun body. The socket receives a controller case (not shown) adapted to contain a multiple contact switch and suitable multiple contact terminals to which the distributor wires are connected. The socket and terminal construction is more fully disclosed in a copending application filed November 1, 1940, Serial No. 363,917.

By reason of the fact that the distributor channel is arranged along the opposite side of the gun from the points of connection with the several gun units which it serves, it is possible to position the connectors 16 so that the distributor wires 20 may be substantially permanent, the distributor wires being entirely within the body of the gun or within the channel and

therefore fully protected from the surge of fluids around the gun body as it is moved through the well or upon discharge of the gun unit. The only wires exposed to the surge of well liquid are the lead wires from the connectors 16 to their respective gun unit plugs; even these wires are set relatively deep in slots 22. Furthermore, the lead wires are replaced with each firing of the gun inasmuch as they form a part of the electrical fuse provided at the inner end of the plug. In other words, the distributor wires form a permanent part of the gun, while the lead wires are replaced.

Also, the discharge or muzzle ends of the gun bores are positioned a maximum distance from the sockets 9 and 15. This is made possible by positioning the distributor wire channel on the opposite side of the gun from the sockets. Otherwise the discharge end of one gun unit would be in proximity to the socket containing the lead wire of the adjacent gun unit. Tests have shown that the detrimental effect of liquid surge around the socket containing the lead wire is very materially reduced when the gun bore is displaced circumferentially therefrom. Apparently, the force of the surging liquid diminishes as much as the square of the distance from the muzzle.

Various changes and alternate arrangements may be made within the scope of the appended claims, in which it is my intention to claim all novelty inherent in the invention as broadly as the prior art permits.

I claim:

1. A gun perforator construction comprising: a gun body having formed therein a plurality of laterally directed gun bores, each intersected by a laterally disposed cartridge bore; a terminal socket adjacent the outer end of each of said cartridge bores; a longitudinally extending distributor wire channel disposed approximately diametrically opposite the outer ends of said cartridge bores and wire passages connecting said channel with said terminal sockets.

2. A gun perforator construction comprising: an elongated cylindrical body member having gun bores and intersecting cartridge bores disposed transversely to the axis of the gun body, a longitudinally extending distributor wire channel approximately diametrically opposite the outer ends of said cartridge bores and wire passages traversing the body member from said channel to points adjacent the outer ends of said cartridge bores.

3. A gun perforator construction, as set forth in claim 1, wherein the different gun bores and different cartridge bores are relatively disposed circumferentially to define helical courses along the gun body, and said distributor wire channel likewise extends helically.

4. A gun perforator construction, as set forth in claim 2, wherein the different gun bores and different cartridge bores are relatively disposed circumferentially to define a helical course along the gun body, and said distributor wire channel likewise extends helically.

5. A gun perforator construction comprising: a cylindrical gun body defining a plurality of laterally directed cartridge bores divided alternately into two sets, the cartridge bores of one set lying on the opposite side of the axis of said gun body from the adjacent bores of the other set; said gun body defining further two sets of laterally directed gun bores, one gun bore for each cartridge bore, each gun bore extending

approximately diametrically opposite the adjacent gun bores of the other set.

6. A gun perforator construction, as set forth in claim 5, wherein the outer ends of both sets of cartridge bores define a single helical path along the body member, and the muzzle ends of the two sets of gun bores define double helical paths along the body member.

7. A gun perforator construction comprising: a cylindrical gun body defining a plurality of cartridge bores divided alternately into two sets, one set of cartridge bores extending on the opposite side of the axis of said gun body from the adjacent bores of the other set; said gun body defining further a laterally directed gun bore for each cartridge, each gun bore extending approximately diametrically opposite the adjacent gun bores of the other set; and said gun body member defining further a longitudinal distributor wire channel disposed approximately diametrically opposite the outer ends of

said cartridge bores; and traversing passages extending from said channel to the outer ends of said cartridge bores.

8. A gun perforator construction, as set forth in claim 7, wherein the outer ends of both sets of cartridge bores define a single helical path along the body member, said channel being disposed helically and the muzzle ends of the gun bores defining double helical paths along said gun body on opposite sides of said channel.

9. A gun perforator construction comprising: a cylindrical gun body defining a plurality of laterally directed cartridge bores divided alternately in two sets, the cartridge bores of one set lying on the opposite side of the axis of said gun body from the adjacent bores of the other set; said gun body defining further two sets of laterally directed gun bores, one gun bore traversing each cartridge bore.
